UNITED STATES PATENT OFFICE.

CHARLES E. HUXLEY, OF AURORA, ILLINOIS, ASSIGNOR OF TWO-THIRDS TO
FREDERICK WAHL AND GEORGE E. RICKER, OF QUINCY, ILLINOIS.

VALVE-REMODELING DEVICE.

SPECIFICATION forming part of Letters Patent No. 651,548, dated June 12, 1900.

Application filed October 2, 1899. Serial No. 732,268. (No model.)

To all whom it may concern:

Be it known that I, CHARLES E. HUXLEY, of Aurora, in the county of Kane and State of Illinois, have invented certain new and useful Improvements in Valve-Remodeling Devices; and I do hereby declare that the following is a full, clear, and exact description thereof, reference being had to the accompanying drawings, and to the letters of reference marked thereon, which form a part of this specification.

This invention relates to an improved device in the nature of a hand implement for remodeling valve-seats, the purpose of the invention being to provide an implement which may be adjustably secured to a valve-casing in position for a cutting-tool, which forms a part of the implement, to operate upon the valve-seat. The implement is similar in character to that shown in my prior United States Letters Patent, No. 614,226, dated November 15, 1898.

The invention herein shown refers more particularly to an improved means for detachably securing the implement to the valve-casing.

Other features of improvements of the character set forth are, however, disclosed, as will hereinafter more fully appear.

The invention consists in the matters hereinafter described, and more particularly pointed out in the appended claims.

In the drawings, Figure 1 is a side elevation of an implement embodying my invention, showing the same in connection with a valve-casing, which latter is shown in central longitudinal section. Fig. 2 is a plan section taken on line 2 2 of Fig. 1. Fig. 3 is a bottom plan view of the implement. Fig. 4 is a plan section taken on line 4 4 of Fig. 1. Fig. 5 is an enlarged vertical section of the implement, showing some of the parts in changed position. Fig. 6 is a cross-section taken on line 6 6 of Fig. 5. Fig. 7 is a view from beneath of the chuck-actuating ring. Fig. 8 is a detail section thereof, taken on line 8 8 of Fig. 7. Fig. 9 is a top plan view of one of the chuck-jaws. Fig. 10 is a side elevation of the spindle which carries the cutting-tool.

In said drawings, A A indicate a valve-

casing, such as that of an ordinary globe-valve, said casing being provided with a valve-seat *a* and with a screw-threaded opening *A'*, which when the valve is in use receives the head which carries the valve-spindle.

B designates a plate which is provided with means by which it may be detachably connected with the valve-casing and serves to support or sustain the other parts of the implement in position for action upon the valve-seat.

C designates a supporting-plate which is secured to the attaching-plate B by means of an annular outwardly-projecting flange *B'*, concentric with and on the outer side of said attaching-plate, said flange being provided with exterior screw-threads for engaging with the interior screw-threads provided in a cylindric recess on the inner side of said supporting-plate. A screw-threaded ring *C'* surrounds the screw-threaded flange *B'* of the attaching-plate below the supporting-plate C and is adapted for contact with said plate, so as to form in effect a jam or locking nut, which acts to hold the plate C firmly in place upon the attaching-plate. Said ring is provided on opposite sides with notches *c'*, adapted to be engaged by a spanner or like tool. Said plate C is provided with a centrally-arranged transverse slot or opening *C²*, and on opposite sides of said slot are formed two parallel guide-flanges *C³* *C³*, provided on their inner faces at their bases with grooves *c*. Between said flanges are located two sliding blocks D, provided at their upper and lower edges with outwardly-extending flanges *d* *d'*, of which the outer flange *d* extends over the top surfaces of the guide-flanges *C³* and the inner flange *d'* engages the grooves *c* therein. Each of said sliding blocks is provided at one end with a laterally inwardly extending arm or cross-piece *D'*, which extends nearly to the inner face of the opposite sliding block. Between said sliding blocks is located a swivel block or head E, which has pivotal connection with said sliding blocks in the manner shown in said prior patent, and to said head is attached a screw-threaded sleeve E', which extends outwardly therefrom. Through said head and sleeve passes a shaft

or spindle F, which is adapted for actuation by means of a crank-arm F', attached to the outer end thereof. Said spindle is provided at its inner end with means for attaching a 5 cutting-tool thereto—such, for instance, as the tap G (shown in the drawings)—and is screw-threaded at its lower end to receive a securing-nut g. The purpose of the sliding blocks D D, together with the swivel-block E 10 and clamping device for holding said parts in position, is to adjustably support the tool-carrying spindle F in proper position with respect to the valve-seat to be operated upon. The details of construction by which these 15 parts are adjusted and held in their adjusted positions are substantially like those shown in my said prior patent, said swivel-block E being pivoted to the sliding blocks D, so as to enable the tool-spindle to be swung in an inclined or oblique position. The sliding blocks are clamped in rigid relation with respect to the guide-flanges C³ by means of set-screws H, which are inserted through said guides and act against the outer face of the sliding 20 blocks. The sliding blocks on the guide-flanges C³ enable the swivel-block to be bodily moved transversely, as may be required, to incline the spindle to bring the cutting-tool accurately in place with respect 25 to the valve-seat. The arms D' of the sliding blocks are provided with set-screws H', which are adapted to bear against the head E, which latter is curved at its inner end to afford a bearing-surface for said screws con- 30 centric with the pivotal axis of the head.

In order to adjust a tool to an angle with respect to the valve-casing, as required where the valve-seat is not parallel with the opening of the valve-casing, it will be necessary to 35 turn the supporting-plate C on the flange B' so as to bring the guide-flanges C³ thereof parallel with the plane of the inclination of the tool-spindle, and this adjustment of the supporting-plate is readily effected by loos- 40 ening the locking-ring C' and then turning the supporting-plate to the desired position, after which said ring will be tightened against the supporting-plate to prevent further turning of said plate and hold the latter fixedly in 45 place.

As a means for feeding or advancing the spindle and the tool as the work progresses devices are provided as follows: The sleeve E' is provided with an external screw-thread, 50 which is engaged by an interiorly screw-threaded sleeve or nut I, provided at its outer end with a radial flange I', constituting a hand-wheel by which the sleeve may be turned. Above the flange I' is a disk I², 55 which is connected with the said flange by two arms i i, and between the said disk I² and said flange is located a collar F², which fits between and engages said flange and disk. Said collar is provided with a set-screw f', 60 which engages at its inner end the spindle F and by means of which said collar may be adjustably secured to the spindle. Said col- 65

lar constitutes a means of holding the sleeve I from endwise movement with relation to the spindle, so that when the sleeve is turned its 70 screw-threaded connection with the sleeve E' will act to advance the spindle and tool to its work. The spindle is cut away on the side thereof engaged by the set-screw f', thereby forming a flat surface f², and said surface is 75 inclined upwardly, as shown in Fig. 5, the dotted line in said figure indicating the original contour of the spindle. The purpose of inclining the surface f² is to prevent the spindle from moving upwardly through the collar 80 F² in the upward thrust given thereto when the sleeve I is turned to feed the tool forward against the work. It will be understood that the collar F² will be locked to the shaft only when a cutting-tool, such as a reamer or the 85 like, is being used, and when a tap is being used the feeding device described will not be required and the spindle will be allowed to slide freely through the sleeve E', so as to follow the tap in its advance movement. The 90 spindle F is provided with a graduated scale, as shown, to enable the operator to readily determine the extent of inward movement when a tap is being used, at which time the spindle passes freely through the sleeve E'. 95 An adjustable collar I³ on the sleeve E' forms a stop for the sleeve I, by which the advance movement of the tool may be accurately limited when the same is being fed forward by 100 the turning of said sleeve I.

Referring now to the means for detachably connecting the attaching-plate to the valve-casing A, these parts are made as follows: The attaching-plate B is provided on its inner side with a plurality of radial grooves B², 105 which are herein shown as formed in thickened parts or ribs in said plate. Within said grooves B² are inserted chuck-jaws B³, which are provided with means for moving the same radially inward and outward upon the plate 110 B. Said grooves are herein shown as made T-shaped in cross-section, and the jaws are provided with oppositely-directed longitudinal flanges which interfit with said groove and prevent the jaws from falling out of 115 place. Said jaws are provided with a plurality of radially-separated offset surfaces b, there being three, as herein shown, and the corresponding surfaces of each of said jaws are formed at an equal distance from the inner ends of the jaws, so that when said jaws are in place within the grooves B² such corresponding surfaces will be included in a circular line concentric with the center of the 120 plate. Said offset jaws are provided with 125 screw-threads, and the jaws are adapted to be moved radially inward and outward, so that the screw-threads of one of the surfaces of each of the jaws will engage the interior screw-threads in the aperture A' of 130 the valve-casing. With this arrangement the screw-threaded radially-arranged jaws form, in effect, a stud secured to the attaching-plate and which has screw-threaded en-

gagement with the aperture A' of the casing. The screw-threaded surfaces adjacent to the outer ends of the jaws will be employed in connection with valve-casings having relatively-large openings A', while those adjacent to the inner ends of the jaws will be employed with smaller valve-casings. Means are provided for simultaneously moving said jaws radially outward and inward to enable the implement to be attached to valves having different-sized openings, and means are also provided for locking said jaws in any adjusted position. The means herein shown for this purpose are made as follows: The upper edges of said jaws within the slots are provided with a plurality of teeth or notches b', which when the jaws are in proper position in the plate B are arranged on a spiral line passing from the inner to the outer ends of the jaws. B⁴ designates a chuck-actuating ring which is located in an annular recess B⁵, formed upon the outer side and adjacent to the periphery of said attaching-plate. Said actuating-ring is provided on its inner face with a spiral screw-thread b², which when the ring is in place upon the plate B engages certain of the teeth or notches b' in the upper face of the jaws B³. The part of said plate occupied by said annular recess B⁵ being in a plane inside of the outer parts of the grooves, openings are formed in said recess opposite to said radial grooves through which said screw-thread of the actuating-ring and teeth of the jaws project and by means of which connection is afforded between the same. Said actuating-ring is provided inside of said screw-threads with an annular bearing-surface b⁴, which engages the upper surfaces of the chuck-jaws B³ and by means of which said jaws are clamped or held in place. Said actuating-ring is provided in its periphery with a plurality of notches b⁵, which are adapted to be engaged by a suitable implement, such as the spanner J shown, by which the said ring may be rotated to move the jaws inwardly or outwardly, as desired. A locking-ring B⁶ surrounds the outwardly-projecting annular flange B' of the attaching-plate above or outside of said actuating-ring and serves when screwed down upon the actuating-ring to force the same against the chuck-jaws, and thereby rigidly lock and hold the same from movement, the bearing-surface b⁴ and also the screw-threaded part of said actuating-ring coming in contact with the teeth of the chuck-jaws when the ring is forced toward the said jaws by the action of the locking-ring. Said locking-ring is provided with notches b⁶, by which it may be engaged by a spanner to move the same into and out of its locking position. As shown in Fig. 5, the locking-ring B⁶ is moved away from the actuating-ring to enable the latter to be turned to adjust the chuck-jaws B³. As a further and separate improvement said chuck-jaws are so arranged that they may be made to engage either an interior or exterior surface of the

valve-casing, so that the implement may be used as well upon a valve-casing in which the head is secured thereto through the medium of external screw-threads as in the instance illustrated. This is accomplished by removing the jaws from the grooves B², reversing and inserting them into said grooves with the screw-threaded surfaces b thereof facing inwardly. In order that the screw-thread of the actuating-ring may accurately engage the teeth b' of the jaws and move said jaws inwardly and outwardly when the latter occupy either of the positions mentioned, the opposite sides of each of the said teeth are oppositely curved, as shown in Fig. 9, the curvature thereof corresponding with the curvature of the portion of the screw-thread of the actuating-ring which engages said teeth. By this means space is provided between said teeth for the short curved portion of the screw-thread which stands opposite the same when the engaging faces of the jaws are facing either inwardly or outwardly. The construction last described is of much importance, as it greatly increases the capacity of the implement for work by enabling it to be used upon valve-casings in which the head is secured thereto either by interior or exterior screw-threads.

The construction described, in which the attaching-plate is provided with a plurality of radially-movable chuck-jaws, with a screw-threaded actuating-ring adapted to bear against the jaws and a locking-ring which forces the actuating-ring into clamping engagement with the jaws, is of great importance, as it enables the implement to be readily adjusted to valve-casings of various sizes and at the same time affords an exceedingly-rigid connection between the same when the jaws have been locked in their adjusted position.

In the operation of the implement when the same is to be employed in connection with a valve-seat which is arranged in a plane parallel with the upper surface of the casing A the chuck-jaws B³ will be moved inwardly against the tool-spindle F for the purpose of centering said spindle, so that the tool connected thereby will accurately engage the valve-seat, after which the jaws will be moved outwardly, with their screw-threaded faces b in contact with the interior screw-threaded valve-casing. Said jaws are shown in Figs. 1, 3, and 5 in position to center the spindle F and are shown in dotted lines in Figs. 1 and 3 in the outer or clamping position. When said jaws are moved outwardly into engagement with the screw-threads of the casing, the inner ends thereof will be moved a sufficient distance from each other to provide room for the required movement of the tool-spindle when the latter is inclined to adapt the cutting-tool to an inclined valve-seat.

I claim as my invention—

1. An implement for remodeling valves comprising an attaching-plate, a rotative and

endwise-movable tool-spindle, chuck-jaws movable radially in said attaching-plate, means for simultaneously moving said jaws inwardly and outwardly, and means for simultaneously clamping said jaws rigidly to said attaching-plate.

2. An implement for remodeling valves comprising an attaching-plate, a rotative and endwise-movable tool-spindle and means for attaching said implement to the valve-casing comprising jaws which are arranged to slide radially in said attaching-plate and are provided with teeth or notches, a rotative, screw-threaded actuating-ring which is movable toward and from the jaws and engages the teeth thereof, and means acting on said ring to force the same into clamping engagement with said jaws.

3. An implement for remodeling valves comprising an attaching-plate, a rotative and endwise-movable tool-spindle, and means for attaching said implement to a valve-casing comprising jaws which are arranged to slide radially in said attaching-plate and are provided with teeth or notches, a rotative screw-threaded actuating-ring engaging said teeth, and a locking-ring having screw-threaded engagement with the attaching-plate and acting against said actuating-ring to force the same into clamping engagement with said jaws.

4. An implement for remodeling valves comprising an attaching-plate having a cylindric, screw-threaded outer surface, a supporting-plate having screw-threaded engagement with the outer surface of said attaching-plate, a locking-ring on said attaching-plate having engagement with the lower face of said supporting-plate, a rotative and endwise-movable tool-spindle mounted on said supporting-plate, and means for attaching the implement to a valve-casing embracing jaws which are movable radially in said attaching-plate, and clamping means for the jaws embracing a screw-threaded locking-ring engaging the screw-threaded part of the attaching-plate.

5. An implement for remodeling valves

comprising an attaching-plate, a supporting-plate connected therewith, a rotative and endwise-movable tool-spindle, and means for attaching said implement to a valve-casing comprising jaws which are movable radially in said attaching-plate and provided on their upper faces with teeth, a rotative actuating-ring provided with a screw-thread adapted to engage said teeth of the jaws, and a locking-ring having screw-threaded engagement with the attaching-plate and acting on the upper face of the actuating-ring to force the same into clamping engagement with the jaws.

6. The combination with an apertured bearing-block, an exteriorly-screw-threaded sleeve attached thereto, a tool-spindle having rotative and endwise-movable engagement with said sleeve and block and provided adjacent to its outer end with a flattened inclined surface, a screw-threaded nut engaging said sleeve, a collar surrounding said spindle in its part containing the flattened inclined surface and engaging said nut by means preventing endwise movement of said parts, and means for locking said collar rigidly to the spindle.

7. The combination with an apertured bearing-block, an exteriorly-screw-threaded sleeve attached thereto, a tool-spindle having rotative and endwise-movable engagement with said block and sleeve, and provided adjacent to its end with a flattened inclined surface, a screw-threaded nut on said sleeve, a collar surrounding said spindle and engaging said nut by means preventing relative endwise movement of said parts and a set-screw passing through said collar and engaging the inclined surface of said spindle.

In testimony that I claim the foregoing as my invention I affix my signature, in presence of witnesses, this 12th day of September, A.D. 1899.
